UNITED STATES PATENT OFFICE.

CARL H. SCHADE, OF DENVER, COLORADO.

IRONING BOARD.

Application filed April 26, 1927. Serial No. 186,619.

This invention relates to improvements in ironing boards of the type employed in homes for ironing the usual home wash.

It is the object of this invention to produce an ironing board which will stand firmly and which can be adjusted to the required height and which shall, at the same time, be so constructed that it can be readily folded into a compact package and which will remain folded when it is suspended from a hook or nail.

It is a further object of this invention to produce an ironing board of such a construction that it will not collapse when being set up and which shall be provided with an auxiliary board for ironing sleeves, a metal support for the iron and a device on which the clothes already ironed can be placed.

The above and other objects that may become apparent as the description proceeds are attained by means of a construction and an arrangement of parts that will now be described in detail, reference for this purpose being had to the accompanying drawings in which the preferred embodiment has been illustrated and in which:

Figure 1 is a perspective view showing my improved ironing board in operative position;

Figure 2 is a longitudinal vertical section of the ironing board;

Figure 3 is a plan view partly in section looking in the direction of arrows 3—3, Fig. 2;

Figure 4 is a view taken along line 4—4, Fig. 2, looking in the direction of the arrows;

Figure 5 is a section taken on line 5—5, Fig. 4;

Figure 6 is a section taken on line 6—6, Fig. 3; and

Figure 7 is a plan view of the under side of the board showing the parts in folded position.

Numeral 1 indicates the ironing board which is of the usual size and shape, and is preferably made of pine or some other suitable wood. The sides of this board are grooved in the manner indicated by numeral 2. Secured to the underside of the board, adjacent the outer edges thereof are clamping springs, which are each provided with two arms 3 that extend in opposite directions from a central loop portion 4. These springs are secured to the under side of the

ironing board by means of screws 5. The extreme ends of arms 3 are bent upwardly and inwardly so as to provide hooks 6, Fig. 1, which engage in the grooves 2 and serve to hold the cloth cover in place. This cloth has not been shown but is invariably employed in connection with ironing boards.

Secured to the underside of the ironing board near its wide end is a transverse board 7. This board is provided near each corner near one of its ends with a lug 8, to which the ends of members 9 and 10 are attached by means of screws or bolts 11. Members 9 and 10 form one of the supports for the ironing board. One end of these members is joined together so as to form a pointed portion 12, in the manner shown in Figure 7. The other ends of members 9 and 10 are each provided with a projecting corner 13 that extends beyond the pivot 11 and which engages the under surface of the board 7 so as to limit the outward movements of members 9 and 10. This is a great convenience in erecting the board as will hereafter appear. Cooperating with members 9 and 10 so as to form a complementary portion of the support is an assembly consisting of a board 14 provided at each end with a projection 15. The notches 16 which are formed by the ends of the board 14 and the sides of the projections 15 receive the side members 9 and 10 in the manner shown quite clearly in Figs. 1 and 7. Secured transversely to the board 14 are arms 17.

These arms are identical in size and shape and extend upwardly in the manner indicated in Figs. 1 and 2. The upper ends of arms 17 are connected by means of a transverse bar 18. Attention is called at this point to the fact that pivot pins 19 extend through the side members 9 and 10 into the lower ends of the arm 17 in the manner shown in Figure 4. This permits arm 17 and board 14 to rotate about the axis of the pivots 19. This rotation is limited, however, by the projecting points 15 which engage the side members 9 and 10 in such a manner as to limit the extent to which these can be swung about the pivots. Two legs 20 and 21 are pivoted at points 22 to the under side of the board 14 in the manner shown quite clearly in Fig. 4. The point at which these arms or legs are pivoted is spaced a short distance from the upper ends and the latter are bevelled so as to engage each other along line 23, when in open position. For the

purpose of making the legs 20 and 21 rotate together and to the same extent, connecting bars 24 have been provided. Each of these connecting bars have their two ends bent at 5 right angles so as to form pivot pins 25 that engage in suitable openings in the legs 20 and 21. Each of these connecting bars has one end connected to one of the legs below the pivots 22 and the other connected to the 10 other leg at a point above the pivot 22 and cross each other in the manner shown clearly in Fig. 4. The purpose of interconnecting the legs 20 and 21 by means of bar 24 is to cause them to move together and to an equal 15 extent. By this means the legs are always adjusted to the same position and thereby the operation of the setting of the board is greatly facilitated. The under side of the board is provided with two rows of notches 20 26 which are adapted to receive the upper ends of the arms 17 in the manner indicated in Fig. 2. When the arms 17 engage the notches farthest from the pivot pin 11 the top of the ironing board will be in its lower- 25 most position. If it is desired to raise the ironing board, the arm 17 may be moved back to one or the other of these notches 26. When the ironing board is to be collapsed, the assembly comprising the arm 17 and the 30 legs 20 and 21 is rotated in the direction of the arrows in Figure 2, until the arm 17 and legs 20 and 21 come to a position in which they lie between the parts 9 and 10 and are parallel with them. The whole support 35 can then be folded against the rear of the ironing board so as to assume the position like that shown in Fig. 7. A loop 27 is secured to the side of board 7 and serves as a means by which it may be supported. 40 Secured to the under side of the ironing board 1 is a small ironing board which has been indicated by numeral 28 and which may be employed for ironing sleeves and similar articles. This small ironing board is se- 45 cured to the under surface of board 7 by means of a bolt or other pivot pin 29. A pin 30 projects from one side of the board 28 on the opposite side of pivot 29 from the nar- 50 row end of the board and this pin acts as a stop which prevents the ironing board 28 from moving past the central position when it is returned to inoperative position, Fig. 3. A board similar to ironing board 28 is also 55 secured to the pivot 29. This board has two parallel arms 31 and 32, and when moved transversely to board 1 these arms will project outwardly so as to form means on which the clothes that have already been ironed may be supported. This board has been in- 60 dicated as a whole by numeral 33 and is provided with a pin 34 that serves the same purpose as pin 30 which has already been de- 65 scribed. When the board is in use, the ironing board 28 and the clothes supporting board 33 may be moved out into the posi-

tion shown in Figure 1, but when the board is not in use, they can be moved into the position shown in Fig. 7.

In order to provide a supporting shelf for the iron, I have provided my board with a metal slide 35 which lies between the under surface of board 1 and the transverse board 7. This metal shelf can be moved inwardly into the position shown in Fig. 7, or outwardly into the position shown in Figures 75 1 and 2. As the outer edge of this shelf is provided with a roll 36, its inward movement is, of course, limited and for the purpose of limiting the outward movement, I have provided the inner corners of the shelf 80 with upwardly bent wires 37 that serve as stops. By using a metal shelf 35 for supporting the flatiron, the danger of setting the ironing board afire is obviated as the metal employed in shelf 35 is incombustible. 85

From the above it will be apparent that I have produced an ironing board of a very simple and substantial construction, that is very neat in appearance and which can be folded very compactly so as to take up but a small amount of room when not in use. The construction is also such that there will be no tendency for the parts to unfold when the board is suspended by the loop 27. The points 13 on side members 9 and 10 assist 90 very greatly in folding and unfolding the board as they prevent the support from rotating more than a predetermined number of degrees about the pivot 11. The ends 15 of the board 14 act as stops that prevent the support, comprising arm 17 and legs 20 and 21, from moving more than a predetermined amount with respect to members 9 and 10. This prevents a collapse of the board in case 95 the upper ends of arm 17 should fail to engage in either of the notches 26. 100

Having thus described the invention what is claimed as new is:

1. In an ironing table assembly, in combination, an elongated ironing board pro- 110 vided with transversely spaced lugs on its underside near one end, a supporting mem- 115 ber comprising two parts, each of which has one end pivotally attached to one of said lugs, and which have their other ends con- 120 nected together, a cross member lying be- 125 tween the two parts of the first supporting member and pivoted to the latter, one end of said cross member having two parallel arms adapted to contact with the under surface of the board and the other end having two legs adapted to contact with a supporting surface, said legs being movable about spaced pivots and means for interconnecting the legs so that they move about their pivots simultane- 130 usly but in opposite directions.

2. In an ironing table assembly, in combination, an elongated ironing board provided with transversely spaced lugs on its under- 135 side near one end, a supporting member

comprising two parts, each of which has one end pivotally attached to one of said lugs, and which have their other ends connected together, a cross member lying between the
5 two parts of the first supporting member and pivoted to the latter, one end of said cross member having two parallel arms adapted to contact with the under surface of the board

and the other end having two legs adapted to contact with a supporting surface, said legs 10 being movable about spaced pivots and means for limiting the movement of the legs about their pivots.

In testimony whereof I affix my signature.

CARL H. SCHADE.
